UNITED STATES PATENT OFFICE

CLAUDE M. DIBBLE, OF JOLIET, ILLINOIS, ASSIGNOR TO MOORE BROTHERS COMPANY,
OF JOLIET, ILLINOIS, A CORPORATION OF ILLINOIS

GAS BURNER

Application filed August 4, 1928. Serial No. 297,459.

This invention relates to gaseous fuel burners and has for its general object to provide a burner of compact construction in which efficiency in operation is promoted and the heating capacity is enlarged in respect of the area of flame propagation.

Numerous other objects and advantages of the invention will be apparent as it is better understood from the following description, which, taken in connection with the accompanying drawing, discloses a preferred embodiment thereof.

In the drawing:

Figure 1 is a plan view of a gaseous fuel burner of one type constructed in accordance with the invention;

Fig. 2 is a vertical sectional elevation on an enlarged scale of the inlet end of the burner;

Fig. 3 is a horizontal section taken on the line 3—3 of Fig. 2;

Fig. 4 is a transverse vertical section taken on the line 4—4 of Fig. 3;

Fig. 5 is another transverse vertical section taken on the line 5—5 of Fig. 3, and

Fig. 6 is a transverse vertical section taken on the line 6—6 of Fig. 3.

The illustrative burner may be made conveniently of a casting 11 comprising a horizontally elongated body 12 of generally rectangular shape in cross section. The inlet end 13 of the burner body is formed with a head 14, the outer surface 15 of which may be cylindrical in shape and provided with clamping projections 16 for the purpose of securing the burner body to the wall of a suitable heating chamber, as for example is disclosed in my companion application Serial No. 297,458 for Letters Patent of the United States for stove constructions, filed of even date herewith, which has resulted in Patent No. 1,822,274, issued September 8, 1931.

The head 14, as shown, is concentrically positioned on the inlet end 13 of the burner body and the rear part of the head merges into a cup-shaped portion 17, the walls of which converge into the constricted part 18 of a Venturi tube 19. The Venturi tube 19 is located concentrically in respect of the longitudinal axis of the burner body and

projects inwardly thereof, as shown in the drawing. From its constricted part 18, the walls of the Venturi tube are flared substantially conically, as shown at 20, and the zone of the maximum diameter of said conical flared portion 20 is located at the outlet 21 of the Venturi tube.

The Venturi tube is provided with a bore 22 for the passage of the gaseous combustibles. This bore 22 consists essentially of a cup-shaped inlet portion 23, which converges from the inlet 24 of the burner body into the constriction 25, in the direction of the flow, and from this constriction 25, diverges because of the conical bore 26 toward the Venturi outlet 21.

The illustrative burner may be operated on the Bunsen burner principle, and for this purpose, the outer face of the head 14 is provided with a closure wall 27 provided with openings 28 for the ingress of air. The closure wall 27 is provided with a central opening 29 to receive the pipe 30 which discharges the gaseous fuel into the cup-shaped inlet portion 24 of the Venturi tube. Mounted on the outer face of the closure wall 27 is a disc 31 also provided with a central opening 32 for the gas pipe 30, and with an inwardly projecting flange 33 which surrounds the gas pipe, as shown in Fig. 2. The disc 31 is provided with air inlets 34, companion to inlets 28 of the closure wall 27, and, by rotating the disc relatively to the closure plate, the registration of the companion inlets 34 and 28 may be varied to regulate the quantity of air introduced into the Venturi tube along with the gaseous fuel. A nut 35 threaded at 36 on the gas pipe 30 may be tightened against the outer face of the disc 31 to retain the latter in adjusted position.

The gas pipe 30 may be provided with a valve 37 of any preferred construction for controlling the supply of gas to the Venturi tube of the burner, and the gaseous fuel may be obtained from any suitable source of supply leading to the installation in which the burner is mounted.

The Venturi tube receives the supply of gaseous fuel and air in the diverging cup-shaped inlet portion 24. From the portion

24, the gaseous fuel and air pass through the constriction 25 in which its velocity is augmented and continue with gradually decreasing velocity through the diverging conical bore 26 of the tube to the Venturi outlet 21. 5 At this outlet 21, the mixture of fuel and air is delivered to the chambers or passageways in the main body portion of the burner. As the gaseous fuel and air pass through the 10 Venturi tube, its velocity is first rapidly increased, which of course is accompanied by a decrease in pressure, and next, the velocity of the gases is gradually decreased as the 15 flow progresses toward the outlet 21 of the tube. The decrease in velocity caused by the diverging conical bore 26 is accompanied by a gradual rise in pressure of the gases. The 20 effect produced by the Venturi tube is to promote the mixing of the air and gaseous fuel and to deliver to the burner channels a proper mixture of fuel and air for ignition and consumption at the nozzles of the burner.

The illustrative burner is constructed to provide an augmented nozzle and consequent 25 flame capacity, yet with conservation of space and proper distribution of the heating effect. The main body 12 of the burner is divided by a longitudinal slot 38 extending parallel to and concentric with the major longitudinal 30 axis of the burner into two legs 39. These legs 39 are respectively located on opposite sides of the major longitudinal axis of the burner and may be connected at the extreme inner end of the burner body by a transverse 35 connecting portion 40. Each leg 39, as shown in Fig. 6, is substantially rectangular in cross section and is provided with a longitudinal bore 41 for the flow of the combustible mixture. As shown in Fig. 3, the bores or 40 chambers 41 extend from the outlet 21 of the Venturi tube toward the extreme inner or rear end 40 of the burner, on opposite sides of the longitudinal axis thereof.

Projecting into the top wall 42 of each of 45 the gas passages 41 are gas nozzles 43, of any preferred construction. As shown in Fig. 1, the gas nozzles 43 are arranged in parallel rows along the legs 39 and extend in series from the inlets of the receiving 50 passages 41 to the extreme inner end 40 of the burner body. If desired, the nozzles of the two inside rows 44 may be arranged parallel with, but in staggered relationship to, the nozzles of the two outer rows 45. 55 This arrangement promotes conservation of space, consistent with a maximum number of gas nozzles leading from the gas passages 41. The gas and air pass along the passages 41 and emerge through the nozzles 42, providing, after ignition, a multitude of jets arranged in rows extending the entire distance of the legs 39 of the burner body.

As shown in Figs. 3 and 4, the inside vertical walls 46 of the gas passages 41 converge 60 at the inlets of the passageways 41 so as to

provide vertical inside faces 47 which are disposed at an angle to the central vertical plane of the burner body and converge into an apex 48 in the direction of the outlet 21 of the Venturi tube. 70

At its outlet 21, the walls of the Venturi tube are sharply flared, as shown at 49, as compared with the main portion of the conical bore 26 and terminate forwardly of the apex 48 of the forwardly converging faces 75 provided by the front terminals of the walls 46 of the gas passages 41. This construction and arrangement provides a distributing chamber 50 located just beyond the outlet 21 of the Venturi tube but just forwardly of the inlets of the gas passages 41. 80

The outer vertical walls 51 and the top and bottom walls 52 and 53 of the gas passages 41 are continued forwardly of the burner body and extend substantially to the burner head 14. These walls provide gas passages or channels 54 extending parallel with and on opposite sides of the central longitudinal axis of the Venturi tube, from the outlet 21 thereof and forwardly of the burner body to a region adjacent to the head 14 and in advance of the constriction 25 of the venturi. As shown in Figs. 2 and 3, the side portions of the walls of the Venturi tube constitute the inner walls of the channels or passages 54 95 and are provided with substantially plane, vertical faces 55 to provide substantially vertical sides for said channels. As shown in Fig. 5, the other walls of the channels are made similarly plane on their inside faces to provide channels 54 which are substantially rectangular in cross section. 100

Projecting through the tops 52 of the channels on the opposite sides of the Venturi tube are series 56 of burner nozzles 42. 105 These series 56 may be arranged in longitudinal rows extending, if desired, as continuations of the outer rows 45 of burner nozzles leading from the passages 41, forwardly and substantially to the head 14 of the 110 burner body.

The mixture of gaseous fuel and air delivered from the outlet 21 of the Venturi tube first passes into the distributing chamber 50, whence it is diverted by the converging walls 47 into two streams. Part of each of the fuel streams on the opposite sides of the longitudinal axis of the burner passes rearwardly through the channels or passageways 41 and is widely distributed into individual 115 jets by the rows of nozzles 44 and 45. Other parts of the fuel streams diverted by the baffle, provided by the hereinbefore described walls 47, pass forwardly through the channels 54 and are distributed similarly by the rows of nozzles 56 into a large number of flame jets on opposite sides of the central Venturi tube, and substantially to the head 14 of the burner body. 120

This construction provides adequate mix- 130

ing facilities for the fuel gas and air and yet greatly augments the flame distribution throughout the burner body. In fact, substantially every part of the burner body is provided with jets of flame. The flame jets on the opposite sides of the Venturi tube serve also to heat the gaseous fuel and air as it passes through the tube and thus assist the mixing operation. At the same time, this wide distribution of the flame is attained without increasing substantially the size of the burner body.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof. Moreover, it is not indispensable that all features of the invention be used conjointly, as they may be advantageously employed in various sub-combinations and other combinations.

I claim:—

1. A gaseous fuel burner, comprising an elongated body provided at one end with a Venturi tube extending inwardly of the body from the gaseous fuel inlet to a distributing chamber located at the outlet of the Venturi bore, said burner body having gas passages extending rearwardly longitudinally from said distributing chamber on opposite sides of the longitudinal central axis of the body to the other end thereof, the inner vertical walls of said passages converging toward the Venturi outlet and into said distributing chamber into an apex to provide baffling means for dividing the gas flow from the Venturi outlet, and said burner body also having gas passages extending forwardly from said distributing chamber and beyond the constriction of the Venturi bore, on each side of the longitudinal central axis of said Venturi tube, and outside rows of fuel nozzles connected with said rearwardly and forwardly extending gas passages and arranged therealong from the rear to the front ends of the burner body, and inside rows of fuel nozzles connected with said rearwardly extending gas passages from the front to the rear ends thereof.

2. A gaseous fuel burner, comprising, an elongated body provided at one end with a Venturi tube extending inwardly of the body from a gaseous fuel inlet to a distributing chamber located at the outlet of the Venturi bore, said burner body having gas passages extending rearwardly from said distributing chamber to the other end of the body, the inner vertical walls of said passages being shaped to provide baffling means for divid-

ing the gas flow from the Venturi outlet, and said burner body also having gas passages extending forwardly from said distributing chamber and beyond the constriction of the Venturi bore, and rows of fuel nozzles connected with both said rearwardly and forwardly extending passages.

3. A gaseous fuel burner, comprising, a burner body, a Venturi tube extending inwardly of the body from the fuel inlet end thereof, a distributing chamber located at the outlet of said Venturi tube, gas flow passages extending on opposite sides of the burner body from said distributing chamber to the rear end of said body, gas flow passages extending from said distributing chamber forwardly on each side of said Venturi tube to the front end of the burner body, baffling means located within said distributing chamber for directing the gas flow into said passages, and series of fuel burner elements connected with each of said passages.

4. A gaseous fuel burner, comprising, a burner body, a Venturi tube extending inwardly of the body from the fuel inlet end thereof, a distributing chamber located at the outlet of said Venturi tube, gas flow passages extending on opposite sides of the burner body from said distributing chamber to the rear end of said body, and gas flow passages extending from said distributing chamber forwardly on each side of said Venturi tube to the front end of the burner body.

5. A gaseous fuel burner, comprising an elongated burner body provided with a central fuel feeding channel extending inwardly from the fuel inlet end of the body toward the rear end thereof, and two fuel feeding and distributing channels one arranged along each side of said fuel feeding channel and separated therefrom by a heat conducting wall.

6. A gaseous fuel burner, comprising a burner body partitioned internally to provide combustible mixture conducting and distributing passages, the top of said burner consisting of a single continuous bounding wall provided with nozzles communicating with said distributing passages and adapted to conduct heat directly to said conducting passage.

7. A gaseous fuel burner, comprising an elongated body generally rectangular in cross-section and having an upper bounding wall arranged substantially in a horizontal plane and provided with nozzle outlets, side distributing passages communicating with said nozzle outlets, and a central inlet passage partitioned from said distributing passages.

8. A gaseous fuel burner, comprising a body partitioned adjacent an end to provide a central Venturi inlet for the combustible mixture and side distributing passages, and hav-

ing burning nozzles communicating with said passages at said Venturi inlet whereby to directly heat by conduction the mixture as it passes through said inlet.

5 9. A gaseous fuel burner, comprising an elongated, generally rectangular, body partitioned internally to provide a central inlet passage for the combustible mixture, and side distributing passageways separated from 10 said inlet passage by partitions extending from an end of said burner part way toward the opposite end.

10 15 10. A gaseous fuel burner, comprising an elongated, generally rectangular, body partitioned internally to provide a central inlet passage for the combustible mixture, and side distributing passageways separated from said inlet passage by partitions extending from an end of said burner part way toward 20 the opposite end, said body being provided with nozzle outlets extending throughout its length.
